FLOAT SWITCH

William R. Jessup, Minneapolis, Minn.

Application July 9, 1937, Serial No. 152,745

5 Claims. (Cl. 200—84)

My invention relates to improvements in float switches for tanks particularly, though not exclusively, for oil tanks for domestic oil burners, an object of the invention being to provide a simple, durable and inexpensive float switch which is readily applicable to any ordinary oil tank, without alteration of the tank, and which is adapted to be quickly and easily adjusted and repaired.

Another object of the invention is to supply a switch of the present character having a housing providing two compartments, one for actuating parts and one for switch parts, each compartment being individually accessible to give access to its respectively contained parts independently of and apart from the parts contained in the other compartment.

A further object of the invention is to supply a float switch, as above, in which one compartment of the housing communicates with the interior of the tank and the other compartment is segregated from the first by means of a partition providing a bearing for a rocker member employed to move a switch part in said second compartment in response to the movement of an actuating member in said first compartment, such construction barring the transmission to said first compartment of burning gases ignited in said second compartment.

With the foregoing and other objects in view, which will appear in the following description, the invention resides in the novel combination and arrangement of parts and in the details of construction hereinafter described and claimed.

In the drawing:

Fig. 1 is a perspective view showing an embodiment of my invention in float switches applied to an oil tank.

Fig. 2 is a vertical sectional view in detail of the switch and a portion of the tank shown in Fig. 1, said view being taken as on line 2—2 of said Fig. 1.

Fig. 3 is a horizontal sectional view taken as on the line 3—3 of Fig. 2 and drawn to a somewhat smaller scale than Fig. 2.

Fig. 4 is a fragmentary longitudinal sectional view of the float showing its adjustable application to the lower end of the float rod.

Fig. 5 is an elevational view of the switch case or housing with the cap removed from the lateral branch thereof, said view showing the switch parts within said branch.

In supplying oil to domestic oil burners, it is common practice to utilize oil tanks of substantially 250 gallons capacity. In purchasing oil in quantity less than 200 gallons, the price is usually greater than that charged for the same quality of

oil in quantity equal to or in excess of 200 gallons. It is, therefore, desirable from an economical standpoint to purchase 200 or more gallons of oil at a time, such method of purchasing being further desirable since it minimizes the frequency of purchases and the inconvenience occasioned in the filling of a tank. With only 50 gallons or less of oil left in a tank when it is capable of receiving a replenishing charge of 200 gallons, comparatively little leeway remains for discovery of the fact that the tank should be replenished. Accordingly, it frequently occurs that the oil supply becomes entirely exhausted with the result that the consumer may be greatly inconvenienced by the failure of his burner for lack of fuel, not to mention the extra expense to which he is put in securing special deliveries of oil and the special services of burner service men which are often required in re-starting a burner. The present invention provides a mechanism which eliminates this inconvenience and expense by immediately informing the user when the oil in the tank reaches a level at which the tank will accommodate a predetermined replenishing charge and yet will continue to supply oil in predetermined quantity.

For the purpose of illustrating the application of my invention, I have shown a conventional oil tank 10 such as used in connection with domestic oil burners, said tank including a body 11 of sheet metal having end walls 12. Welded to the lowermost portion 14 of the body 11 are brackets 15 which rest on legs 16 fitted with floor flanges 17. In the uppermost portion 18 of the body 11 of tank 10 are tapped fittings 19, 20 and 21, fitting 19 accommodating a filler pipe 22, fitting 21 accommodating a vent pipe 23 and fitting 20 providing a third opening into the tank to give access thereto or for any other desired purpose.

My improved float switch, as illustrated, comprises an upright tubular case or housing 24 having an open upper end 25. The lower end of the case 24 is closed and formed to provide a plug 26 which is threaded at 27 to screw into a threaded fitting such as fitting 20 in the tank 10. If desired, a sealing gasket (not shown) may be placed between the shoulder 28 on case 24 and the lip 29 of the fitting 20. To facilitate screwing the plug 26 into fitting 20, the lower end of the case 24 is constructed with a wrench engaging portion 30, 50 preferably hexagonal in form.

The case 24 has a lateral tubular branch 31 with an open outer end 32. A partition 33 is formed at the junction between the case 24 and the branch 31, a compartment 34 being provided 55

in the case proper at one side of said partition and a compartment 35 being provided in the branch 31 at the other side of the partition. This partition is formed with an elongated boss 36 issuing 5 into the compartment 35 in said branch 31.

The upper end 25 of the case 24 is threaded externally as at 38. A cap 39 screws upon these threads 38 and serves to close the open end 25 of said case, a gas tight connection between the 10 cap 39 and the case proper, being provided by the employment of a gasket 40 between said cap and the lip 37 of the case. The outer end 32 of the branch 31 is provided with external threads 42 to receive a cap 43, a sealing gasket 44 being 15 interposed between said cap 43 and the lip 41 of said branch 31.

A mercury switch 45 is employed, the same being of ordinary construction and such as is now well known in the art. This switch includes a 20 tube or capsule 46 of glass or other suitable material, said tube being provided with contacts 47 projecting into the interior thereof. Within the tube is a globule of mercury 48 which is adapted to make an electrical connection between the two 25 contacts 47 when the tube 46 is in one inclined position (dotted lines, Fig. 5) and to break such connection when said tube is in an oppositely inclined position (solid lines, Fig. 5). Also within the tube 46 is an inert gas in the presence of 30 which sparking is effectually minimized. Flexible conductors 51, connected with the contacts 47, connect the switch 45 in the circuit in which it is used.

The switch 45 is mounted for oscillation, as 35 follows: The boss 36 on the partition 33 has an axial bore 52 extending therethrough and through said partition. This boss 36 constitutes a bearing for an arm 54 which is in the form of a shaft, the same being bent at one end portion thereof to provide a crank 54b and being reduced and threaded at the other end portion thereof to provide a shouldered support 54c. The cylindrical shank portion 54a of the arm 54 is revolutely disposed within the bore 52 of the boss 45 36 with the crank 54b thereon within the compartment 34 of the case 24 and the support 54c within the compartment 35 of the branch 31. A carrier plate 53 is centrally apertured to receive the support 54c formed by the reduced end of 50 the arm 54, said plate 53 being clamped between the shoulder (not shown) of said support and a clamping nut 58 threaded on said support. Riveted to the carrier-plate 53, above the center thereof, is a clip 55 formed with bent fingers 56 55 which embrace the tube 46 and hold it in a fixed position relative to said carrier-plate, as shown. Riveted also to the carrier-plate 53, but below the center thereof, is a weight 57, cylindrical in form, the axis of said weight being disposed in parallelism with respect to the axis of 60 the shank portion 54a of the arm 54. Unimpeded, this weight 57 serves to turn the rock arm 54 in a clockwise direction, as seen in Fig. 5, and thus shift the switch tube 46 from the position thereof 65 shown in dotted lines (Fig. 5) to the position shown in solid lines. Formed integrally with the wall of the case or housing branch 31 is an inwardly issuing lug 31a forming a limit stop against which the weight 57 abuts, when it 70 reaches the bottom of its gravitating swing.

The mechanism for operating the switch 45 to close the circuit therethrough includes a float rod 63 vertically disposed and guided for vertical movement in a guide tube 64. This tube is 75 attached to the plug 26, the upper end of said

tube being pressed into an axial bore 65 formed in said plug. Attached to the lower end of the rod 63 is a float 66 comprising an elongated hollow body of light sheet metal having an axial sleeve 66a therein. The float rod 63 extends 5 through said axial sleeve 66a of float 66, said float being held in place on said rod between spaced collars 66b secured to said rod by means of set screws 66c. The float 66 is of such diameter as to be insertable into the tank through the 10 opening in the fitting 20.

The upper portion of the float rod 63 is threaded as at 71 and a metal disc 72, centrally apertured to receive the rod, is applied to the threaded portion of said rod between two nuts 15 73 and 74 which engage said disc at either side thereof and rigidly clamp it in place on said rod. This disc 72 overlies the crank 54b of arm 54 and, upon the descent of the float rod 63, said disc acts to engage said crank and turn the rock arm 20 54, against the influence of the weight 57, into position closing the switch 45. A stop nut 69, threaded on the float rod 63, is disposed thereon in position to engage the upper end of the guide tube 64 and arrest the descent of said float rod 25 when the crank 54b is turned far enough to close the switch 45. The ascent of the float rod 63 is limited by the cap 39 against which the upper end of said float rod normally abuts. The adjustment of the disc 72 on rod 63 provides for the 30 engagement of said disc with the crank 54b of arm 54 earlier or later in the descent of said rod 63, such adjustment being made, if desired, to supplement the adjustment of the float 66 on said rod 63. The relative angular relation of the 35 switch tube 46, weight 57 and crank 54b of arm 54 is such that the weight 57, unimpeded, will, by gravity, cause the switch tube 46 to assume position as shown in solid lines in Fig. 5, wherein the switch 45 is open and, at the same time, 40 will cause the crank 54b of arm 54 to assume an angular position somewhat above the axis of the shank portion 54a of the said arm. This relation of parts obtaining, the crank 54b of the rock arm 54 is swung downwardly by the disc 72, upon the descent of the rod 63, thus turning the arm 54 and shifting the tube 46, against the action of the weight 57, into a position as shown in dotted lines in Fig. 5, wherein the switch 45 is closed. 45

The disc 72 being disposed above the crank 54b, the ascent of float rod 63 is unimpeded thereby. Owing to its form, the disc 72 properly engages the crank 54b, regardless of the angular disposition of the float rod 63 in relation to the case 24.

The flexible conductors 51 of switch 45 are connected to contact posts 77 extending through the wall of the housing branch 31, said posts, in turn being connected in a circuit 81. This circuit 81 may include an electric lamp 82 and the secondary 83 of a transformer 84 whose primary 85 is connected to any suitable source of electric current. The transformer 84 furnishes electrical current for operating the lamp 82 when the switch 45 is closed, said lamp 82 being at 60 some convenient locality where an attendant will promptly observe the lamp when lighted.

In applying the device to any given oil tank, the principal adjustment to be made to suit the particular tank, is the adjustment of the float 70 66 on the float rod 63. In making this adjustment, the float 66 is secured to float rod 63 in such position thereon that the buoyancy of the float in the oil will support the rod 63 and hold it with the upper end thereof abutting against the cap 75

39 only until enough of the oil has been consumed to permit the replenishing of the supply in predetermined quantity. When this stage of the oil in the tank has been reached the float 5 66 together with the float rod 63 should promptly begin to descend as the oil continues to be drawn from the tank. In such descent of the float rod, the disc 72 engages the crank 54b of rock arm 54 and turns said arm to close the switch 45 (dotted 10 lines, Fig. 5), whereby notice is given, through lamp 82, of the demand of the tank for the usual refilling charge and of the limited oil supply remaining in the tank. In some installations, it is convenient in very closely adjusting 15 the device to supplement the float adjustment by adjusting the disc 72 on the float rod 63, said disc is caused to engage the crank 54b of arm 54 earlier in the descent of the float 66, whereby the switch 45 is more promptly closed after the 20 tank can accommodate the predetermined refilling charge. By elevating the disc 72 on rod 63, the opposite result is obtained. Depending upon any adjustment of the disc 72 that may be made, the stop nut 69 is correspondingly adjusted to keep the dead weight of the float 66 and rod 63 from being applied to the rock arm 54 through the engagement of the disc 72 with the crank portion 54b of said arm. When the signal lamp 82 has been lighted by closing the switch 30 45, said lamp remains lighted until oil is added to the tank. As the oil rises in the tank, upon the refilling thereof, the float 66 and float rod 63 rise with the oil until the upper end of the rod 63 reaches the cap 39. During this short upward movement of the float rod 63, the disc 72 frees the crank 54b of the rock arm 54, said arm being thereupon turned by the weight 57 into position to open the switch 45 (solid lines, Fig. 5) and cut off the current to the lamp 82. As the 40 replenishment of the oil supply in the tank continues, the float is held submerged in the oil and no further movement of the switch actuating mechanism occurs until the level of the oil again falls below the critical level. At such time, the 45 float 66 and rod 63 start to descend, the continuing descent thereof causing the turning of the crank 54b, through the medium of disc 72, and the consequent closing of the switch 45. When it is desired to ascertain the amount of oil 50 within the tank before the critical level has been reached, the cap 39 is unscrewed and removed from the case 24, thus permitting rod 63 to rise through the action of the float 66. By reference to the lowermost of the visible graduations 67 55 which are suitably formed on the rod 63, the quantity of oil within the tank can be quite accurately determined. Normally, the caps 39 and 43 are kept in place to confine the gases from the oil in the tank to said tank and to 60 the case 24.

The length of the boss 36 and the clearance between the shank 54a of arm 54 and the wall of the bore 52 in said boss are such as to remove any possibility of an explosion of gases in the 65 compartment 34 of case 24 and the tank 10, as the result of an explosion in the switch compartment 35 of branch 34. Ample clearance in its bearing for the free rocking movement of the arm 54 is necessary, yet the length of the bearing 70 in relation to the clearance is such that burning gases, fired within the switch compartment 35, cannot make their way about the shank 54a of arm 54 to the compartment 34 of the case 24. In practice, I have found that a bore in the boss 36 75 of one and one-eighth inches in length and a

clearance of five one thousandths of an inch between the shank 54a and the wall of such bore will provide for the free rocking movement of the arm 54 and, too, will effectively confine burning gases to the switch compartment 35 of the 5 case 24, whereby dependability of operation, without danger of explosion in the oil tank, is assured.

Changes in the specific form of my invention, as herein disclosed, may be made within the scope of what is claimed without departing from 10 the spirit of my invention.

Having described my invention, what I claim as new and desire to protect by Letters Patent is:

1. A unitary device of the character described comprising an upright case formed with a horizontal branch, the case having an opening at its upper end and a removable cap normally closing said opening, said branch having an opening at its outer end and a removable cap normally closing the opening therein, a plug at the lower end of the case for attachment to a fitting in an opening in the top of a tank, a float rod, said plug having a bore therein slidably receiving said rod for vertical movement, a float mounted on the lower portion of said rod and adapted with said portion of said rod to be passed through said tank fitting and positioned within the tank, an arm rockably mounted within the device, the outer end of said arm being disposed within said branch and the inner end thereof within the case, an electric switch within said branch, said switch having a part movable with said arm, means within said branch acting on said arm to move the arm in one direction and "throw off" the switch, an actuating member mounted on the upper portion of the float rod and adapted, upon the descent of said rod, to engage the inner end of said arm from above and move the arm to "throw on" the switch, the opening in the case initially admitting said actuating member to the case, the opening in the branch initially admitting said switch and companion parts to said branch, the removal of the cap from the case normally affording access to said actuating member and to the interior of the case and its contained parts independently of and apart from the branch and the parts contained therein, the removal of the cap from the outer end of said branch normally affording access to the switch and companion parts independently of and apart from the case proper and the parts contained therein. 20 25 30 35 40 45 50 55 60 65 70 75

2. A unitary device of the character described comprising an upright case having a plug at its lower end for attachment to a fitting for an opening in the top of a tank, a float rod, said plug having a bore therein slidably receiving said rod for vertical movement, a float mounted on the lower portion of said rod and adapted with said portion of said rod to be positioned within said tank, said case having a horizontal branch, an electric switch within said branch, an arm rockably mounted within the device, the outer end of said arm being disposed within said branch and the inner end thereof within the case, said switch having a part movable with said arm, means acting on the outer end of said arm to move the arm in one direction and "throw off" the switch, an actuating member adjustably mounted on the upper portion of the float rod and adapted, upon the descent of the float rod, to engage the inner end of said arm from above and move the arm to "throw on" the switch, a sealing cap at the top of said case, said cap being removable to lend access to the interior of the case and its con- 75

- tained parts, and a second sealing cap applied to the outer end of said branch and removable therefrom to lend access to its contained switch and companion parts independently of and apart from the case proper and the parts contained therein.
3. A unitary device of the character described comprising an upright case having a plug at its lower end for attachment to a fitting for an opening in the top of a tank, a float rod, said plug having a bore therein slidably receiving said rod for vertical movement, a float mounted on the lower portion of said rod and adapted with said portion of said rod to be positioned within said tank, said case having a horizontal branch, a partition segregating the interior of the case from the interior of said branch, said partition having an elongated bearing boss thereon projecting into said branch and formed with an axial cylindrical bore extending therethrough and through said partition, an arm having a cylindrical shank portion and a crank at one end thereof, a mercury switch within said branch, said shank portion of said arm being rockably received in said bore, the crank on said arm being disposed within the case proper and the end of said shank opposite said crank being disposed with said branch, a carrier member mounted on said end of said shank, said switch being mounted on said carrier member, a weight also mounted on said member and acting on said arm to turn the same in one direction to "throw off" the switch, an actuating member mounted on the upper portion of the float rod and adapted, upon the descent of said rod, to act upon said crank and turn the arm in the other direction to "throw on" the switch, the clearance between the shank of said arm and the wall of the bore in said bearing boss being limited in relation to the length of said bore to prevent burning gases, ignited by the switch in said branch from reaching the gases in the case through said partition.
4. A unitary device of the character described comprising an upright case having a plug at its lower end for attachment to a fitting for an opening in the top of a tank, a float rod, said plug having a bore therein slidably receiving said rod for vertical movement, a float mounted on the lower portion of said rod and adapted with said portion of said rod to be positioned

within said tank, said case having a horizontal branch, a partition segregating the interior of the case from the interior of said branch, said partition having an elongated bearing boss thereon, formed with a bore extending therethrough and through said partition, an arm movably received in said bore, an electric switch within said branch, the outer end of said arm being disposed within the case proper and the inner end thereof within said branch, said switch having a part movable with said inner end of said arm, means acting on said arm to move the same in one direction to "throw off" the switch, an actuating member mounted on the upper portion of the float rod and adapted, upon the descent of said rod, to act upon and move said arm in the other direction to "throw on" the switch, the clearance between said arm and the wall of the bore in said bearing boss being limited in relation to the length of said bore to prevent burning gases, ignited by the switch in said branch, from reaching the gases in the case through said partition.

5. A unitary device of the character described comprising an upright case for intercommunicating attachment to a tank, a float rod having one end portion thereof disposed within the case, a float mounted on the other end portion of said rod and adapted therewith to be positioned within said tank, said case having a branch, a partition segregating the interior of the case proper from the interior of said branch, an arm extending through the partition, the outer end of said arm being disposed within the case and the inner end thereof within said branch, a bearing on said partition movably supporting said arm, an electric switch within said branch, said switch having a part movable with said inner end of said arm, means acting on said arm to move the same in one direction to "throw off" the switch, an actuating member mounted on said portion of the float rod within the case and adapted, upon the descent of said rod, to act upon and move said arm in the other direction to "throw on" the switch, said bearing for said arm being formed to prevent burning gases, ignited by the switch in said branch, from reaching the gases in the case through said partition.

WILLIAM R. JESSUP.
